UNITED STATES PATENT OFFICE.

BORIS ANOSCHENKO, OF PHILADELPHIA, PENNSYLVANIA.

AUTO-SIGNAL.

1,359,308.

Specification of Letters Patent. Patented Nov. 16, 1920.

Application filed July 8, 1919. Serial No. 309,272.

To all whom it may concern:

Be it known that I, BORIS ANOSCHENKO, a citizen of Russia, residing at Philadelphia, in the county of Philadelphia and State of Pennsylvania, have invented new and useful Improvements in Auto-Signals, of which the following is a specification.

This invention relates to signal apparatus and it has more particular reference to devices of the foregoing nature such as are applicable for use on automobiles and the like, and which simulate the action of the hand when extended at arm's length to give an indication to following traffic and 10 pedestrians that the vehicle is about to make a turn or take a curve.

The main object of this invention is to provide a novel form of signal apparatus of the type referred to which is automatically operated whenever the driver changes 20 speed, applies the brakes or commences to take a curve.

A further object of my invention is to furnish a signal apparatus more especially 25 for use on automobiles in which the signal giving element or semaphore approximates in its movement to effective position the natural throw of the human arm and hand.

Another object of this invention is to 30 provide a signal apparatus for automobiles which is equally effective when employed either by day or at night.

A still further object of the invention is the provision of a signal apparatus for automobiles which is simple in construction, readily and easily installed, neat and attractive in appearance, thoroughly reliable and efficient in its purpose, cheap to manufacture and most important of all is automatic in action under all conditions when once set up and adjusted.

With these and other objects in view, the invention consists essentially in the novel features of construction, combination and 45 arrangement of parts, as will be hereinafter fully described and more specifically pointed out by the appended claims.

In the further disclosure of the invention reference is to be had to the accompanying 50 sheets of explanatory drawings, constituting a part of this specification, in which like characters of reference denote the same or similar parts in all the views; and in which:—

Figure 1— is a perspective view of a por-

tion of the fore part of an automobile having my improved signal apparatus fitted thereto.

Fig. 2— is an end elevation of my improved signal apparatus in collapsed position, parts being broken away or in section for the sake of cleanness. 60

Fig. 3— is a vertical section taken on the line 3—3, in Fig. 2, and looking in the direction of the arrows. 65

Fig. 4— is a vertical section taken on the line 4—4 in Fig. 2, and looking in the direction of the arrows.

Fig. 5— is a face view of the signal apparatus in extended position. 70

Fig. 6— is a plan of the same.

Fig. 7— is an enlarged detail of one of screen supporting members hereinafter more particularly described.

Fig. 8— is an enlarged detail of a washer 75 element, and,

Fig. 9— is an enlarged detail of a guiding eye for attachment to the steering post.

Referring more particularly to the views, the numeral 10, designates a fragmentary 80 portion of an automobile, 11 the windshield, 13, the clutch lever, 14 the ordinary or service brake, 15, the emergency brake, 16 the gear shift and 17, the steering wheel.

My improved signal apparatus is designated in its entirety by the letter A— and it is arranged to be operated as hereinafter 85 fully described by means of a cable 18,— which passes around guide rollers or pulleys 19, 19 arranged where desired, and is connected to the clutch lever 13. A branch connection 20, from the cable 18, passes longitudinally along the steering post 21, through a guide or guides 22,— Fig. 9— 90 clamped thereto by clamping screws 23, and 95 is attached at its free end to one of the arms of the steering wheel 17.

Another branch connection, 18', may also be made between the cable 18, and the emergency brake 15, so that when the latter is 100 operated the signal apparatus will also be actuated.

The free end of the cable 18, is lead to and 105 passed once completely around a grooved pulley 24 and is secured at 24' firmly thereto. The pulley 24, is keyed or otherwise secured on a shaft 25, freely revoluble in appropriate bearings horizontally of the standards 26, 26. Secured at one end in a hole 27, at right angles to the axis of the 110

shaft 25, is a cord or cable 28, which passes through a hole in the bracket 29, beneath which is seated an inverted somewhat conically shaped sleeve 30, and thence axially 5 of a strong compression spring 31, at the lower end whereof it passes into and is secured in a conically shaped stop plate or movable member 32.

Secured to one face of the pulley 24, are 10 a pair of spaced plates 33, between which and said pulley 24, are journaled rollers 34, 35, the former of which has rolling contact with a cam 36, and the latter with a cam 37, integral with or securely mounted 15 on a shaft 38, mounted in bearings transversely of the apparatus A—. Mounted on and securely fixed to the shaft 38, is a lever or arm 39, which is pivotally connected at its free end to one arm 40 of a lazy tongs 20 system of levers 41, the central pivots 42 whereof are in the nature of flanged sleeves in the bores whereof are soldered or firmly fixed the ends 43,—Fig. 7—of somewhat U-shaped bent wires 44, which serve as a support 25 for the flexible band 45 that constitutes the body portion of the signal proper and simulates in appearance an extended human arm and hand 46. The other or opposed arm 47 of the lazy-tongs system of levers 30 41, is freely rotatable on a fixed shaft 48, and the outer or free ends of the system are connected together at 49, where there is attached a suitable socket 50, for an electric incandescent lamp 51, the wires whereof 35 are inclosed in a cable 52, which is threaded through the aforesaid hollow pivots 42, and connects with a make and break device 53. This make and break device may conveniently consist of a lever 54, to one end where- 40 of is attached at 55, the end of the cable 52, which is threaded through the aforesaid central pivots 42, and the end pivot 42^a of the lazy-tongs system of levers 41, while the other end thereof constitutes a cranked 45 part 56, and said lever 54 is pivoted at 57. The end of the cranked part 56, is arranged to cooperate with the end 58, of the lazy-tongs system 41 when the device is closed up or out of use—as shown clearly in 50 Fig. 4—so that the circuit to the lamp 51, is broken, a contractile spring 59, serving to close the circuit or bring the contacts 60, 61, into engagement when the signal is moved to signaling position. It will of 55 course be readily understood that a push button or switch not shown, is fitted in connection with the electric circuit to the apparatus—or contact 61 for example—to cut-off the current to the lamp 51, during 60 daylight, and that any other appropriate make and break device may be employed and actuated by the lazy tongs system 41.

In use it will be readily seen that when the clutch lever 13, is depressed a pull will 65 be exerted on the cable 18, which will cause

the pulley 24 to be rotated thereby winding the cord 28, about the shaft 25 in opposition to the spring 31. Similarly when the steering wheel 17 is rotated a pull will be exerted on the cable 18 by said cable winding around the steering post 21; or, when the emergency brake 15 is operated a like action will take place. The rotation of the pulley 24 and with it the shaft 25, swings the plates 33 and roller 34, which swings 70 the cam 36 in the direction of the arrow 1, in Fig. 3, which causes the shaft 38 to be turned and thereby swinging the lever 39 and thus causing the lazy-tongs system of levers 41 to be projected outwardly in an 75 arcuate manner while at the same time they will be expanded and stretch the flexible band 45 to the position shown in Fig. 5, with the terminal hand end 63 extended horizontally. Concurrent with the foregoing 80 operation the circuit will be closed to the lamp 51 and a visible indication given when the apparatus is used after dark.

When the roller 35 has moved to the position directly below the axis of the shaft 35, 90 the cam 37 will have been moved downwardly through approximately 180° or a half turn while the cam 36 will have been swung upwardly to a corresponding extent. On releasing the pressure on the clutch lever 95 13, or reversing the action of the steering wheel 17, the extended parts of the signal apparatus will be returned to their normal position by the action of the spring 31, and the roller 34, moving the cam 36 downwardly which results in the return of the signal into its casing or box 64 and the shutting off of the light.

From the foregoing description it will be apparent to those skilled in the art to which 105 this invention appertains that by providing a bracket 65, adapted to support the entire device on one or both of the side posts 12, of an automobile shield that I provide a very simple and attractive apparatus for 110 the purposes specified and while there has been described and illustrated one convenient embodiment thereof, I wish to reserve the right to make such changes and modifications as will be necessary to adapt the invention to different types of self propelled vehicles, these changes and other modifications however being limited by the spirit and scope of the appended claims.

Having described my invention what I 120 claim is,—

1. In a device of the character described, the combination with a casing, of an operating shaft journaled in said casing; a pulley shaft journaled in the casing, a pulley on 125 the pulley shaft, a cable wound on to the pulley and serving to rotate said pulley shaft when the cable is unwound therefrom, cams on said operating shaft, one of said cams serving to bring about operation of the 130

operating shaft in one direction and the other cam serving to bring about operation of the operating shaft in the other direction, means carried by said pulley to be actuated therewith and coöperating with said cams to actuate said operating shaft and means in said casing and associated with said pulley shaft to return said operating shaft and said cams to normal position after said pulley and pulley shaft and cams have been initially actuated to actuate said operating shaft.

2. In a device of the character described, the combination with a casing, of an operating shaft journaled in the casing, a pulley shaft journaled in the casing, a pulley on said pulley shaft, a cable wound on to said pulley and a cam and roller connection between said pulley and said operating shaft for the 10 operation of the latter when the said pulley and pulley shaft and cams have been initially actuated to actuate said operating shaft.

pulley is actuated by partially unwinding the cable therefrom.

3. In a device of the character described, the combination with a casing, of an operating shaft journaled in the casing, a pulley shaft journaled in the casing, a pulley on said pulley shaft, a cable wound on to said pulley, a cam and roller connection between said pulley and said operating shaft for the 15 operation of the latter when the said pulley is actuated by partially unwinding the cable therefrom, and spring actuated means in said casing and associated with said pulley shaft to return said pulley and said operating shaft to normal position upon the 20 subsequent release of the cable for the rewinding of the latter upon the pulley.

In testimony whereof I affix my signature.

BORIS ANOSCHENKO.
